CLAIM

The ornamental design for a display screen or portion thereof with graphical user interface, as shown and described.

DESCRIPTION

FIG. 1 is a front view of a display screen or portion thereof with graphical user interface, showing our new design; and, FIG. 2 is an enlarged view thereof.

The broken lines depicting the display screen or portion thereof and portions of the graphical user interface form no part of the claimed design.

1 Claim, 2 Drawing Sheets

FIG. 1

FIG. 2
